UNITED STATES PATENT OFFICE.

ALF PIPPING, OF ALTOONA, PENNSYLVANIA.

MOLD.

Application filed March 10, 1921. Serial No. 451,254.

To all whom it may concern:

Be it known that I, ALF PIPPING, a citizen of the United States, residing at Altoona, in the county of Blair and State of Pennsylvania, have invented certain new and useful Improvements in Molds, of which the following is a specification.

This invention relates to metal founding.

A primary object is to provide improved means whereby special castings can be produced through the use of a special mold made up to retain its shape after the casting has been removed, thus obviating the necessity of building up a new mold prior to the pouring process.

Another object of this invention is to produce a mold that is readily changed in shape to produce different shaped castings.

A still further object of this invention is to provide a mold that is made up of a plurality of units which are adapted to be readily positioned in a vertical plane and clamped in position by a pressure brought to bear upon them in a horizontal plane.

With the above and other objects in view which will be more readily apparent as the nature of the invention is better understood, the same consists in the novel construction, combination and arrangement of parts as will be hereinafter pointed out fully, illustrated and claimed.

It will be readily understood by those skilled in the art to which this invention belongs that the same is quite susceptible to various changes or modifications without departing from the spirit or scope of the invention but a preferred and practical embodiment of the invention is shown in the accompanying drawings in which:

Figure 1 is a vertical longitudinal sectional view of the present improvements, showing the rods or wires on an enlarged scale.

Figure 2 is a horizontal sectional view of the construction shown in Figure 1.

Figure 3 is a vertical cross-sectional view.

Like reference numerals refer to similar parts throughout the several figures of the drawings.

In carrying out this invention I use instead of the usual molding loam a plurality of small rods or wires designated by the numeral 10. These wires are adapted to be placed in the drag 11, above and around the pattern 12 which rests upon a molding board adapted to be laid across the face of

the drag 11, the drag 11 is provided with means for forcing all the rods or wires 10 together, such that when the pattern 12 is removed the shape of the pattern remains imbedded in the surface. The means for bringing pressure upon the rods 10 may be brought about in several different ways but a simple method is shown wherein a movable end 13 of the drag 11 is connected with a screw 14 which passes through the side 16 of the drag.

A rotation of the screw either serves to tighten or loosen the rods 10 in the drag.

Having thus formed the mold in the drag the protruding ends of the rods being cut off before the same is turned over leaving the face of the pattern uppermost. The other half of the pattern is then superposed upon the lower half and the cope 17 is placed on the drag as shown in the drawings. An earthen tube 18 is then placed above one portion of the pattern and the rods 10 are then dropped in and around the top half of the pattern. This having been accomplished the rods are tightened in place through a device similar to the one attached to the drag. The cope is then removed from the drag and the pattern removed from both the cope and the drag. After this is done a facing F of sand with a mixture of loam may be spread over the surface wherein the pattern rested, in order to prevent the molten metal from welding to the surface of the rods 10, during the process of pouring. This facing S is of course only necessary when metal is being molded and the rods 10 are of metal to prevent adhesion of metal to metal. When molding celluloid, wax or rubber, such facing will not be required. Before the pouring is accomplished some molding loam should be placed around the top of the tube 18 in order to prevent the metal which naturally will fall around the tube from amalgamating with the metal in the rods 10.

It will be quite readily understood that this invention is applicable to molding castings in the drag only in which case no flask is needed and the mold is faced in this case the same as if the cope is used.

It will be observed that this invention is applicable to the use of producing castings having the form of the pattern and also the reverse of the pattern, the latter being accomplished by first using the pattern in the regular way in which certain of the rods

forming the mold will protrude above the adjacent rods due to the irregular outline of the pattern. The rods thus protruding are then cut away and the rods thus cut are 5 pushed back toward the mold board. The outline thus formed is the reverse of the pattern and castings made in this mold will be the reverse of those made from the pattern.

I claim:

- 10 1. A mold forming device including a drag, a movable end in the drag, means for moving said end, a plurality of relatively small rods adapted to be positioned in the drag, a pattern for forming a mold 15 with the rods, and a facing for the mold.
2. A mold forming device including a drag and cope, means for forming a mold chamber consisting of a plurality of rods

adapted to rest perpendicularly on the pattern to be molded, means for retaining the shape of the molds in the drag, cope and means forming a gate for pouring metal into the mold without the same amalgamating with the rods, and a facing for the mold.

3. A mold forming device including a drag, a plurality of rods of uniform length arranged parallel to each other within the drag and adapted to be shifted longitudinally to conform to the face of a pattern while loosely held in the drag, and means 30 for binding the rods together to hold them rigidly in set molding position, the portion of said rods projecting beyond the drag after setting being cut off.

In testimony whereof I affix my signature.

ALF PIPPING.
